UNITED STATES PATENT OFFICE

153,300

DESIGN FOR A BOTTLE STOPPER

Andrew W. McDonald, Caledonia, Ill.

Application December 26, 1947, Serial No. 143,362

Term of patent 14 years

(Cl. D58—10)

To all whom it may concern:

Be it known that I, Andrew W. McDonald, a citizen of the United States, residing at Caledonia, in the county of Winnebago and State of Illinois, have invented a new, original, and ornamental Design for a Bottle Stopper, of which the following is a specification, reference being had to the accompanying drawings forming a part thereof.

In the drawings:

Fig. 1 is a plan view.

I claim:

The ornamental design for a bottle stopper, substantially as shown.

ANDREW W. McDONALD.
